United States Patent Office

Des. 188,858
Patented Sept. 20, 1960

188,858

TOY BANK

Jerome J. Levison, Union City, N.J., assignor to Hoover Products, Inc., Youngstown, Ohio, a corporation of Ohio

Filed Nov. 12, 1959, Ser. No. 58,307

Term of patent 14 years

(Cl. D34—5)

The dominant features of my design reside in the portions shown in full lines.

I claim:

The ornamental design for a toy bank, as shown and described.
